(57) **CLAIM**

The ornamental design for a folding knife, as shown and described.

DESCRIPTION

FIG. 1 is a perspective view of the folding knife shown in the open position;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a cross-sectional view of the folding knife taken at line 8-8 shown in FIG. 2;

FIG. 9 is a cross-sectional view of the folding knife taken at line 9-9 shown in FIG. 2;

FIG. 10 is a perspective view of the folding knife shown in the closed position;

FIG. 11 is a front elevation view of the folding knife shown in FIG. 10;

FIG. 12 is a rear elevation view of the folding knife shown in FIG. 10;

FIG. 13 is a right elevation view of the folding knife shown in FIG. 10;

FIG. 14 is a left elevation view of the folding knife shown in FIG. 10;

FIG. 15 is a top plan view of the folding knife shown in FIG. 10;

FIG. 16 is a bottom plan view of the folding knife shown in FIG. 10;

FIG. 17 is a perspective view of a folding knife according to another embodiment shown in the open position;

FIG. 18 is a front elevation view of the folding knife shown in FIG. 17;

FIG. 19 is a rear elevation view of the folding knife shown in FIG. 17;

FIG. 20 is a right elevation view of the folding knife shown in FIG. 17;

FIG. 21 is a left elevation view of the folding knife shown in FIG. 17;

FIG. 22 is a top plan view of the folding knife shown in FIG. 17;

FIG. 23 is a bottom plan view of the folding knife shown in FIG. 17;

FIG. 24 is a cross-sectional view of the folding knife taken at line 24-24 shown in FIG. 18;

FIG. 25 is a cross-sectional view of the folding knife taken at line 25-25 shown in FIG. 18;

(Continued)

FIG. 26 is a perspective view of the folding knife of FIG. 17 shown in the closed position;
 FIG. 27 is a front elevation view of the folding knife shown in FIG. 26;
 FIG. 28 is a rear elevation view of the folding knife shown in FIG. 26;
 FIG. 29 is a right elevation view of the folding knife shown in FIG. 26;
 FIG. 30 is a left elevation view of the folding knife shown in FIG. 26;
 FIG. 31 is a top plan view of the folding knife shown in FIG. 26;
 FIG. 32 is a bottom plan view of the folding knife shown in FIG. 26;
 FIG. 33 is a perspective view of a folding knife according to another embodiment shown in the open position, where the closed position is the same as FIGS. 10-16;
 FIG. 34 is a front elevation view of the folding knife shown in FIG. 33;
 FIG. 35 is a rear elevation view of the folding knife shown in FIG. 33;
 FIG. 36 is a right elevation view of the folding knife shown in FIG. 33;
 FIG. 37 is a left elevation view of the folding knife shown in FIG. 33;
 FIG. 38 is a top plan view of the folding knife shown in FIG. 33;
 FIG. 39 is a bottom plan view of the folding knife shown in FIG. 33;
 FIG. 40 is a cross-sectional view of the folding knife taken at line 40-40 shown in FIG. 34; and,
 FIG. 41 is a cross-sectional view of the folding knife taken at line 41-41 shown in FIG. 34.
 The broken lines depict portions of the folding knife in which the design is embodied that are not considered part of the claimed design.
